REMOTE INDICATING SYSTEM

Arthur J. Johnston, Aldan, Pa., assignor to General Electric Company, a corporation of New York

Application April 24, 1931, Serial No. 532,609

3 Claims. (Cl. 177—353)

My invention relates to remote indicating systems and particularly to systems for indicating various quantities or characters at a remote point by means of electric lamps. My invention is especially adapted for use in electric score boards in which various numerals representing players, innings, downs, scores, results, etc., may be quickly and readily controlled from a remote point in accordance with the necessary requirements.

10 One object of my invention is to provide an improved remote indicating system of this character.

My invention will be better understood from the following description when taken in connection with the accompanying drawing and its scope will be pointed out in the appended claims.

Referring to the accompanying drawing, Fig. 1 illustrates diagrammatically an electric indicating system embodying my invention whereby a group of lamps may be selectively lighted to form any digit. Fig. 2 indicates how the various digits are formed by the lighted lamps and Fig. 3 illustrates an indicating board embodying my invention, whereby the results of an athletic event, such as a race, may be indicated.

Referring to Fig. 1, 1 represents a group or bank of twenty-four lamps, L—1 to L—24 inclusive, arranged in four vertical rows of six lamps each. In accordance with the embodiment of my invention shown in Fig. 1, the lamps are arranged to be selectively lighted to form any digit but it is obvious that my invention is not limited in its broadest aspects to an arrangement for indicating any particular group of characters. In order to control the lamps L—1 to L—24 inclusive in accordance with the digits to be formed thereby, ten keys K—0 to K—9 inclusive are provided which selectively control the connection of four relays A, B, C, and D, to a suitable supply circuit 2. The four relays A, B, C, and D in turn control the connections of the twenty-four lamps L—1 to L—24 to a supply circuit 3 so as to light the proper lamps to form the desired digit.

As shown in the drawing, the keys K—0 to K—9 respectively control the circuits of the lamps L—1 to L—24 inclusive so as to form the digits 0 to 9. For example, when the key K—0 is operated, it completes across the supply circuit 2 obvious energizing circuits for the relays C and D which in turn by means of their contacts complete the circuits of the necessary lamps so that the lighted lamps form the digit 0. When the key K—1 is operated, the relay A is connected across the supply circuit 2 so that the circuits of the necessary lamps to form the digit 1 are com-

pleted across the supply circuit 3. Similarly, when the keys K—2 to K—9 inclusive are respectively operated, the proper combination of relays is energized to effect the lighting of the proper lamps to form the corresponding digit.

In order to simplify the description, the following tables have been prepared which list the various lamps which are lighted to form the various digits and the contacts through which the circuits of the lighted lamps are completed across the supply circuit 3 when the keys K—0 to K—9 are operated.

When key K—0 is operated, relays C and D are energized and the following lamps are lighted to form the digit 0 in the manner shown in Fig. 2:

Lamp lighted	
L2 circuit completed through d9	
L3 circuit completed through d12	75
L5 circuit completed through b11, d15 and d11	
L8 circuit completed through c7	
L9 circuit completed through c1 and d1	
L12 circuit completed through d14 and c15	
L13 circuit completed through b3 and d1	
L15 circuit completed through d5	30
L17 circuit completed through b5 and c6	
L20 circuit completed through d7 and d5	
L22 circuit completed through d15 and d11	
L23 circuit completed through d11	85

When key K—1 is operated, relay A is energized and the following lamps are lighted to form the digit 1 in the manner shown in Fig. 2:

Lamp lighted	
L3 circuit completed through a11	90
L7 circuit completed through a3, c5 and d2	
L11 circuit completed through d13 and a11	
L15 circuit completed through a3, c5 and d2	
L19 circuit completed through a3, c5 and d2	95
L23 circuit completed through c10 and a9	

When key K—2 is operated, relay C is energized and the following lamps are lighted to form the digit 2 in the manner shown in Fig. 2:

Lamp lighted	
L2 circuit completed through c4	
L3 circuit completed through c11	
L5 circuit completed through b11, a8, c9 and a10	
L8 circuit completed through c7	105
L11 circuit completed through d13 and c11	
L14 circuit completed through d6, c13 and b15	
L17 circuit completed through d8 and c6	
L21 circuit completed through b7, d6, c13 and b15	110

- L22 circuit completed through a_8 , c_9 and a_{10}
 L23 circuit completed through c_9 and a_{10}
 L24 circuit completed through a_{13} , d_6 , c_{13} and
 b15
- 5 When key K—3 is operated, relays B and C are energized and the following lamps are lighted to form the digit 3 in the manner shown in Fig. 2:
- 10 Lamp lighted
 L1 completed through b_1 , d_3 and c_6
 L2 completed through c_4
 L3 completed through c_{11}
 L4 completed through b_1 , d_3 and c_6
 15 L8 completed through c_7
 L11 completed through d_{13} and c_{11}
 L16 completed through b_8
 L17 completed through d_8 and c_6
 20 L20 completed through a_2 and b_8
 L22 completed through a_8 and b_{14}
 L23 completed through b_{14}
- When key K—4 is operated, relays A and B are energized and the following lamps are lighted to form the digit 4 in the manner shown in Fig. 2:
- 25 Lamp lighted
 L3 circuit completed through a_{11}
 L6 circuit completed through b_2 , b_9 and c_7
 L7 circuit completed through a_3 , c_5 and d_2
 30 L9 circuit completed through c_{14} , b_{13} and d_4
 L11 circuit completed through d_{13} and a_{11}
 L13 circuit completed through b_9 and c_7
 L14 circuit completed through a_{12} and b_{10}
 L15 circuit completed through a_3 , c_5 and d_2
 35 L16 circuit completed through b_8
 L19 circuit completed through a_3 , c_5 and d_2
 L23 circuit completed through b_{14}
- When key K—5 is operated, relay B is energized and the following lamps are lighted to form the digit 5 in the manner shown in Fig. 2:
- 40 Lamp lighted
 L1 circuit completed through b_1 , d_3 , b_4 and a_4
 L2 circuit completed through b_6 and c_6
 45 L3 circuit completed through b_{12}
 L4 circuit completed through b_1 , d_3 , b_4 and a_4
 L5 circuit completed through c_8 , a_8 and b_{14}
 L9 circuit completed through c_{14} , b_{13} and d_4
 50 L10 circuit completed through c_3 , c_2 and b_6
 L11 circuit completed through d_{13} and b_{12}
 L16 circuit completed through b_8
 L17 circuit completed through d_8 , b_4 and a_4
 L20 circuit completed through a_2 and b_8
 55 L22 circuit completed through a_8 and b_{14}
 L23 circuit completed through b_{14}
- When key K—6 is operated, relays A and D are energized and the following lamps are lighted to form the digit 6 in the manner shown in Fig. 2:
- 60 Lamp lighted
 L—2 circuit completed through d_9
 L—3 circuit completed through d_12
 L—5 circuit completed through c_8 , d_{15} and d_{11}
 65 L—9 circuit completed through a_5 and d_1
 L—10 circuit completed through c_3 , d_7 and d_5
 L—11 circuit completed through c_{12} and d_{12}
 L—13 circuit completed through b_3 and d_1
 L—16 circuit completed through d_5
 70 L—17 circuit completed through b_5 and d_3
 L—20 circuit completed through d_7 and d_5
 L—22 circuit completed through d_{15} and d_{11}
 L—23 circuit completed through d_{11}
- 75 When key K—7 is operated, relays A and C are energized and the following lamps are lighted to form the digit 7 in the manner shown in Fig. 2:
- Lamp lighted
 L1 circuit completed through c_2 , a_1 , b_5 and c_6
 L2 circuit completed through c_4
 L3 circuit completed through c_{11}
 L4 circuit completed through c_2 , a_1 , b_5 and c_6
 L8 circuit completed through c_7
 L11 circuit completed through d_{13} and c_{11}
 L14 circuit completed through a_{12} and c_{15}
 L17 circuit completed through b_5 and c_6
 L21 circuit completed through b_7 , a_{12} and c_{15}
- When key K—8 is operated, relay D is energized and the following lamps are lighted to form the digit 8 in the manner shown in Fig. 2:
- Lamp lighted
 L2 circuit completed through d_9
 L3 circuit completed through d_{12}
 L5 circuit completed through c_8 , d_{15} and d_{11}
 L8 circuit completed through d_{10} and a_6
 L10 circuit completed through c_3 , d_7 and d_5
 L11 circuit completed through c_{12} and d_{12}
 L13 circuit completed through b_3 and d_1
 L16 circuit completed through d_5
 L17 circuit completed through b_5 and d_3
 L20 circuit completed through d_7 and d_5
 L22 circuit completed through d_{15} and d_{11}
 L23 circuit completed through d_{11}
- When key K—9 is operated, relays B and D are energized and the following lamps are lighted to form the digit 9 in the manner shown in Fig. 2:
- Lamp lighted
 L2 circuit completed through d_9
 L3 circuit completed through d_{12}
 L5 circuit completed through c_8 , d_{15} , d_{11}
 L8 circuit completed through d_{10} and a_6
 L10 circuit completed through c_3 , d_7 and d_5
 L11 circuit completed through c_{12} and d_{12}
 L12 circuit completed through d_{14} and b_{10}
 L16 circuit completed through d_5
 L20 circuit completed through d_7 and d_5
 L22 circuit completed through d_{15} and d_{11}
 L23 circuit completed through d_{11}
- The score board, shown in Fig. 3 is designed to indicate the numbers of the contestants finishing first, second and third respectively in an athletic event. In order that a number containing two digits may be shown, two lamp units 1 are mounted adjacent to each other in the score board at the places where it is desired to show the numbers. Each lamp unit is controlled by its own control unit similar to that one shown in Fig. 1 so that if it is desired to show the number 12 came in second, key K—1 associated with the middle left-hand lamp unit and key K—2 associated with the middle right-hand lamp unit are operated. Obviously, however, if it is so desired the same result may be obtained by means of a single key (not shown) which, when operated, completes the same circuits as are completed by the operation of the two keys K—1 and K—2 respectively associated with the two middle lamp units.
- While I have shown a score board for indicating two digit numbers, obviously my invention is applicable to systems for indicating numbers having more or less than two digits.
- It will be seen that my improved remote control system embodies a minimum amount of apparatus. Since only four relays are required, only five conductors are required between the lamp unit and the controlling point. Also since a maximum of two relays of a unit are energized at

any time, only two-circuit control keys are required for each unit. Furthermore I have arranged the circuits of the lamps in each unit so that not more than three lamps can be simultaneously energized through any set of relay contacts.

While I have in accordance with the patent statutes shown and described my invention as applied to a particular system and as embodying various devices diagrammatically indicated, changes and modifications will be obvious to those skilled in the art and I therefore aim in the appended claims to cover all such changes and modifications as fall within the true spirit and scope of my invention.

What I claim as new and desire to secure by Letters Patent of the United States, is:

1. In a remote indicating system, a group of electric lamps arranged so that any digit can be formed by lighting the proper lamps in the group, a supply circuit, and means for selectively controlling the connections of the lamps to said supply circuit to cause the lamps to be lighted in the proper combinations to form any digit including four relays, each relay having a plurality of front and back contacts, direct connections between said contacts and lamps for completing the circuits of the proper lamps in said group to form said digits when said relays are energized in different combinations of less than three at a time, and means for controlling the energization of said relays in accordance with the digit to be formed by said lamps.

2. In a remote indicating system, a group of electric lamps arranged so that any digit can be formed by lighting the proper lamps in the group,

a supply circuit, and means for selectively controlling the connections of the lamps to said supply circuit to cause the lamps to be lighted in the proper combinations to form any digit consisting of four relays each relay having a plurality of front and back contacts, direct connections between said contacts and lamps for completing the circuits of the proper lamps in said group to form said digits when said relays are energized in different combinations of less than three at a time and so that three lamps are the maximum number connected in series with any relay contact under any normal operating conditions, and means for controlling the energization of said relays in accordance with the digits to be formed by said lamps.

3. In a remote indicating system, twenty-four electric lamps arranged in four rows of six lamps each, a supply circuit, and means for selectively controlling the connections of the lamps to said supply circuit to cause the lamps to be lighted in the proper combinations to form any one of the ten digits consisting of four relays each relay having a plurality of front and back contacts, direct connections between said contacts and lamps for completing the circuits of the proper lamps in said group to form said digits when said relays are energized in different combinations of less than three at a time and so that three lamps are the maximum number connected in series with any relay contact under any normal operating condition, and means for controlling the energization of said relays in accordance with the digits to be formed by said lamps.

ARTHUR J. JOHNSTON.
